COMPRESSOR

William R. Brown, Chicago, and Nigel J. Collings,
Elmhurst, Ill., assignors to W. R. Brown Corporation,
Chicago, Ill., a corporation of Illinois

Application July 29, 1940, Serial No. 348,263

4 Claims. (Cl. 230—234)

The invention relates to air or gas compressors and has as its general aim the provision of a machine of this nature which is simple in construction, efficient in operation, and inexpensive to manufacture.

Another object of the invention is to provide a novel construction whereby economical manufacturing processes, such for example as die castings or stampings, may be largely used with entirely satisfactory results.

Another object is to provide new and improved supporting means which substantially eliminates vibration and noise.

A further object is to provide a novel means for supporting the movable parts of a compressor unit in the casing which is particularly advantageous where the casing is a die-cast or stamped structure.

Another object is to provide a new and improved casing in which the casing is formed of longitudinally divided half-sections arranged to be secured together in a novel manner.

Other objects and advantages will become apparent in the following description and from the accompanying drawings, in which:

Figure 1 is a view primarily in side elevation but partially in axial section of a compressor embodying the features of the invention.

Fig. 2 is a transverse sectional view taken along the line 2—2 of Fig. 1.

Fig. 3 is a view of a detail of assembly as seen from the line 3—3 of Fig. 2.

Fig. 4 is a disassembled view of the casing of the compressor in Fig. 1.

Fig. 5 illustrates fragmentarily a compressor having a modified form of casing.

With reference to the drawings in which an exemplary form of diaphragm type of compressor is shown, the numeral 10 designates a casing which houses the operative elements of the compressor and carries a head 11 in which the air or gas flow controlling means is located. In the present embodiment the casing 10 is a die cast or stamped structure fashioned, as shown in Fig. 4, of two semi-cylindrical sections 12 and 13. The sections are complementary and when secured together form a tubular casing having open ends. It will be evident that the sections may be other than semi-cylindrical in shape.

Means is provided on the casing sections for definitely locating the sections in proper relationship during assembly. Thus, one longitudinal margin of each section has an outstanding projection 14 located on the circular plane of the section and arranged for interfitting engagement with a complementary recess 15 in the meeting edge of the other section. Near one end of each section (in this instance the lower end, Fig. 4), each longitudinal marginal portion has an outstanding lug or finger 16 thereon located within the circular plane of the sections and arranged to extend into

overlapping relation to the marginal edge portions of the opposite section. As shown, the lugs on the opposed margins are not aligned, but are offset to the extent that in assembly the lugs on one section have a side abutting relation with the lugs on the opposite section. The interconnecting elements on the casing sections facilitate assembly by locating the parts in proper operative relationship and, after assembly, the elements tend to maintain such relationship.

The sections may be positively secured together in any suitable manner as by traversing bolts. A particular form of securing means for the lower portion of the structure is shown in Figs. 1 and 4. Thus, each section has near its lower end a radial inwardly extending tubular member 17, 18 which opens through the wall of its casing section and tapers inwardly. The members as shown meet approximately on the axis of the casing and preferably have an abutting relation. The ends may also be caused to interfit as by reducing the diameter of the end portion of one member, herein the member 17, to provide an endwise facing annular shoulder 19 and an end portion receivable in the end of the opposite member 18. The tubular members are united by suitable securing means, such as the headed bolt 20 and nut 21, which, when they are respectively inserted in the tubular members, engage the tapering internal walls to insure that the sections will be rigidly drawn together. Preferably, one of the members, for instance the member 18, has an internal annular flange 22 providing a seat for a nut of small diameter.

The opposite or upper ends of the casing sections are secured together as by means of pairs of outstanding opposed flanges 23 apertured, as at 24, to receive a bolt or like securing means (not shown). Similar means may, if desired, be used at the lower portion of the casing in lieu of the members 17, 18. The upper edges of the casing sections have outstanding flanges 25 appropriately bored and tapped to receive screws 26 (Fig. 1) for securing the head 11 to the casing. Spaced inwardly a short distance from the upper end of each casing section is a comparatively shallow outwardly facing annular shoulder 27, the purpose of which will be presently described.

One of the casing sections, herein the section 13, has an annular flange or boss 28 cast thereon forming a part of a bearing assembly 29 (Fig. 1) for a drive shaft 30 and a driven shaft 31. The compressor unit, as a whole, is supported almost wholly by the drive shaft 30, which shaft is usually the armature shaft of a driving motor (not shown). The driven shaft carries a crank 32 which includes an eccentric crank pin 33 for engagement with the lower end of a connecting rod 34. The upper end of the connecting rod terminates in a flat head 35 for supporting a piston 36. A pull plate 37 carries an axially located

screw 38 which extends through the piston into engagement with the connecting rod head 35 to secure these parts together. Marginally the pull plate engages the inner margin of an apertured flexible diaphragm 39 to bind the diaphragm against an opposed surface of the piston.

The annular shoulder 27 is in the nature of a ledge which provides a seat for a smoothly finished member which traverses the meeting lines of the sections and provides a continuous, smooth surface for coaction with the movable elements of the compressor represented in the present exemplary structure by the diaphragm. As shown in Figs. 1 and 4, this member is an annular member 40 having a part dimensioned to seat on the ledge. In the present instance, the upper or outer face of the member terminates a short distance from the upper end edges of the casing sections, but otherwise the axial length thereof is as desired. In the diaphragm-type compressor the outer margin of the diaphragm 39 extends into overlying relation to the outer face of the ring 40 within the confines of the casing sections and is there fixed by the peripheral engagement therewith of a concave or cup-shaped fixed valve bridge or head 41 which is, in turn, held against the diaphragm by a rim 42 on the head 41. It will be noted that the ring 40 provides a continuous, unbroken support for the operating structure of the compressor and, in a casing composed of longitudinally divided sections, the ring traverses the gaps or spaces between the meeting edges of the sections to prevent leakage of air or gas from the chamber 43 between the flexible diaphragm 39 and fixed bridge or head 41.

The head 41 is hollow and with the valve bridge 41 defines a space 44 with which an outlet 45 for compressed air or gas communicates. The bridge 41 carries a suitable air or gas inlet valve 46 and outlet valve 47 which valves, respectively, are check valves to permit a flow of air or gas into the chamber 43 on the intake stroke of the piston and, thence, on the exhaust stroke through outlet valve 47 into the space 44. If desired, a safety valve 48 may be provided on the head in communication with the space 44.

Since the compressor unit is primarily supported by the driving shaft 30, means is provided for preventing the rotation of the compressor unit with the shaft. In the present instance, the rotation preventing means includes means for dampening or absorbing the vibrations resulting from operation of the device. Referring to Fig. 1, the numeral 49 designates a continuation of the base on which the driving motor is mounted. The base may, however, be a separate fixed part. Secured on the base, and substantially in axial alignment with the casing 10, is a sleeve 50 dimensioned to encircle the lower portion of the casing in spaced relation thereto. A band 51 of rubber or other suitable pliable, resilient material is interposed between the sleeve 50 and the casing 10. The parts are so dimensioned that the lower end of the casing may move to a limited extent without coming into contact with the wall of the sleeve. Rotation of the casing is thereby prevented, yet the casing may vibrate as the compressor operates without transmission of such vibrations to the sleeve and thence to the base. Hence, noise and vibration are substantially eliminated. It may be noted that the telescoping relation of the sleeve and casing, and the generally intermediate position of the band 51, permits of relative axial adjustment through a considerable distance.

Referring to Fig. 5, the casing illustrated therein differs from the casing previously described in that it has on both sections internal bearing supports 28^a for the crank shaft which are alike. Thus, a single die may be employed for both casing sections whether the compressor be one which has a single piston or one having a pair of angularly related pistons driven from a common crank. The casing structure shown in Fig. 10 may also be die cast as a single unitary member. While in this case the casing would have no meeting edges, as in the case of a sectional casing, the single structure does not readily lend itself to the formation in the die casting operation of a shoulder or ledge of sufficient width to afford adequate support to the operating structure. A narrow ledge, indicated at 52 and corresponding to the ledge 27 on the sectional casings, may, however, be formed without difficulty. Consequently, in the single die-cast structure, a ring 53, comparable to the ring 40, is seated on the ledge 52 for supporting, as shown, the outer margin of the flexible diaphragm 38. The remaining structure of the compressor illustrated in Fig. 5, is substantially the same as that shown in Figs. 1 to 4.

While the invention is susceptible of various modifications and alternative constructions, we have shown in the drawings and have herein described in detail the preferred embodiment, but it is to be understood that we do not thereby intend to limit the invention to the specific form disclosed, but intend to cover all modifications and alternative constructions falling within the spirit and scope of the invention as expressed in the appended claims.

We claim as our invention:

1. A casing for a compressor having, in combination, semi-cylindrical, die-cast casing sections, means for securing said sections together including a member on each section extending radially toward the axis thereof, said members being arranged for end-to-end registration, and means for connecting said members together.
2. A casing for a compressor having, in combination, casing sections, means for securing said sections together including radially extending inwardly tapering tubular members on said sections arranged for end-to-end interengagement, and connecting means seated in said members and engaging the walls thereof for securing said members together.
3. A casing for a compressor having, in combination, semi-cylindrical die cast casing sections, and means for securing said sections together including fingers on each section extending into overlapping marginal engagement with the opposite section, and interfitting notches and lips on the meeting edges of said sections.
4. In a compressor of the character described, the combination of a casing formed of semi-cylindrical mating casing sections fitting together along longitudinal lines, means for securing said sections together, a separate ring at one end of said casing substantially concentric therewith and providing a continuous supporting surface at said end and across the lines of division between the casing sections, a compressor means associated with said casing including a driven diaphragm abutting said ring, and a casing end section secured to said casing and binding said diaphragm against said ring.
